UNITED STATES PATENT OFFICE

ELI CROSSLEY, JR., OF MANCHESTER, ENGLAND, ASSIGNOR TO CHARLES A. GOSLETT, OF CHICAGO, ILLINOIS.

PULLEY.

SPECIFICATION forming part of Letters Patent No. 486,631, dated November 22, 1892.

Application filed August 13, 1892. Serial No. 443,008. (No model.) Patented in England August 21, 1890, No. 13,121.

To all whom it may concern:

Be it known that I, ELI CROSSLEY, Jr., a subject of the Queen of Great Britain, residing at Manchester, in the county of Lancaster, England, have invented a new and useful Improvement in Pulleys, (for which I have obtained a patent in Great Britain, No. 13,121, dated August 21, 1890,) of which the following is a specification.

10 My invention relates to an improvement in drums or pulleys adapted to transmit power or be driven through the medium of belts or bands which pass over them and provided at intervals upon their circumferential faces 15 with strips of friction material to enhance their gripping effect upon the belts or bands.

My objects are to provide a drum or pulley of the above class with friction-strips of an improved construction and to provide improved means for securing the strips in place.

In the drawings, Figure 1 is a perspective view of a drum or pulley provided with my improvement; Fig. 2, a section taken on line 2 of Fig. 1; Fig. 3, a section taken on line 3 of Fig. 2; Fig. 4, a section taken on the same line as Fig. 2, but illustrating another construction; Fig. 5, a section on line 5 of Fig. 4; Figs. 6, 7, 8, and 9, broken plan views of pulley-rims, showing different ways of applying my improvement thereto; and Fig. 10, a section taken on line 10 of Fig. 9 and showing friction-pieces employed in that construction.

A is a drum or pulley having a rim A'. In the construction shown in all the figures, except Fig. 9, the rim A' is provided with shallow recesses t, extending in a direction cross-wise of the rim. Extending through the rim at the said recesses are openings t'.

B B are pieces or strips of friction material, 40 preferably of rubber, though they may be of any suitable material having a frictional property superior to that of the material of which the rim A' is formed. One form of the strips B is that shown in Figs. 1, 2, and 3. 45 They are of a length equal to that of the recesses t and are provided on their under surfaces with reduced extensions or lugs B', preferably cast integral with the strips, and which coincide with the openings t' to pass 50 through the latter, as shown. Extending through each lug B', preferably in the direc-

tion of the length of the strip, are two openings s, to receive cotters s'. When a strip is placed in position, its under surface between the lugs B' is in contact with the surface of the base of the recess t and the openings s are at the under surface of the rim A, and the cotters s', when passed through the openings s, are in contact with and bear against the under surface of the rim, whereby the rim at 60 the recesses t is clamped between the cotters and shoulders, afforded at the junction of the lugs with the strips, and the strips thus held rigidly in place. The outer surface of the strips B are preferably convex in cross-section and at their lateral edges extend flush with the outer surface of the rim A'. The strips thus afford convex protrusions of frictional material, which grip the belt and have a tendency to prevent its slipping. By preference the strips are placed at comparatively-short intervals apart around the rim A', so that a belt will be engaged by a number of the friction-strips at one time.

In the construction shown in Fig. 6 the recesses t for the strips B extend each only part way across from side to side of the rim of the pulley, alternate recesses being toward one edge of the rim and the alternate recesses intermediate of the others being toward the opposite side of the rim.

In the construction shown in Fig. 7 the recesses t for the strips B extend all in the same direction at an angle to the perpendicular of the sides of the rim A', and in the construction shown in Fig. 8 the recesses for the strips B are in a line having abrupt angulations giving a zigzag form. The strips B in Figs. 6, 7, and 8 may be constructed like those described and fastened in place in the same manner.

In the construction shown in Figs. 4 and 5 the recesses t are of dovetailed form in cross-section, the openings t' being of the width of the bases of the said recesses. The strips are 95 on opposite sides, beveled down to a sharp edge, and are sprung into the recesses t to extend therein, as shown, the lugs passing through the openings t' and the strips held in place by cotters s' in the same manner as 100 before described, in connection with the construction shown in Figs. 1, 2, and 3.

In the modification shown in Figs. 9 and 10, instead of the recesses t of the elongated form shown in the other figures, lines of perforations or openings q are provided, the openings being countersunk at the outer surface of the rim to afford recesses. Pieces of friction material—such as rubber—having heads q' , fitting into the countersunk recesses, and reduced extensions or shanks q^2 , are placed in the said openings. Through the shanks q^2 are openings to receive cotters s' , which hold the pieces of friction material in place in the same manner described in connection with the strips B. The heads q' are rounded, and when the pieces are placed in position they afford convex knobs or buttons upon the surface of the rim A'.

A drum or pulley provided with my improvements in either of the forms described has in operation a greater gripping effect upon a belt than any other pulley or drum of which I am aware, and while it affords greater driving-power to the device, permits the belts to be comparatively slack. It is well known that where belts are stretched tightly the wear and tear thereof in operation are great in proportion to their tension, and my construction, which permits the belts to be comparatively slack, has a tendency to prevent this wear and tear to a great degree.

Because in the main figure of the drawings I have illustrated the drum or pulley provided with friction-strips of the construction shown in Figs. 2 and 3, these strips are not to be regarded, necessarily, as the preferred form. In many cases, especially where the pulley is to be revolved at a high rate of speed, the strips shown in Figs. 4 and 5 set into dovetailed recesses t may be preferred.

Each recess t may be provided with any desired number of openings t' , the strip B being formed with as many reduced extensions or lugs B' as there are openings to receive them.

What I claim as new, and desire to secure by Letters Patent, is—

1. In a belt drum or pulley, the combination of a rim thereon provided with openings through it and recesses in its outer surface at the said openings, pieces of friction ma-

terial fitting into the said recesses to extend beyond the outer surface of the rim and provided with reduced extensions passing through the said openings, and securing means for the strips engaging the said reduced extensions at the under side of the rim, substantially as described. 55

2. In a belt drum or pulley, the combination of a rim thereon provided with openings through it and recesses in its outer surface at the said openings, pieces of friction material fitting into the said recesses to extend beyond the outer surface of the rim and provided with transversely-perforated reduced extensions passing through the said openings, 65 and cotters bearing against the under side of the rim and engaging the said reduced extensions at the perforations, substantially as and for the purpose set forth.

3. In a belt drum or pulley, the combination, with the rim, of elongated recesses formed therein at intervals around its periphery and extending in a direction crosswise of its circumference, openings through the rim at intervals in each of the said recesses, strips of friction material in the said recesses, projecting beyond the outer surface of the rim and provided with reduced extensions passing through the said openings, and securing means for the strips engaging the said reduced extensions at the under surface of the rim, substantially as described. 70 75

4. In a belt drum or pulley, the combination, with the rim, of dovetailed recesses formed therein at intervals around its periphery, openings through the rim at the said recesses, pieces of friction material of dovetail form in cross-section set into and fitting the said recesses projecting beyond the outer surface of the rim and provided with perforated reduced extensions which pass through the said openings, and cotters extending through the perforations in the said reduced extensions and bearing against the under surface of the rim to secure the said pieces in 95 place, substantially as described. 85 90

ELI CROSSLEY, JUNIOR.

In presence of—

ELI CROSSLEY, Senior.
